UNITED STATES PATENT OFFICE

99,475

DESIGN FOR A BAG OR ANALOGOUS ARTICLE

Peter Das, Passaic, N. J., assignor to Standard Brands Incorporated, New York, N. Y., a corporation of Delaware

Application March 10, 1936, Serial No. 61,553

Term of patent 14 years

To all whom it may concern:

Be it known that I, Peter Das, a citizen of the United States, residing at 31 Belmont Place, in the city of Passaic, county of Passaic, and State of New Jersey, have invented a new, original, and ornamental Design for a Bag or Analogous Article, of which the following is a specification, reference being had to the accompanying drawing, forming part thereof.

The different varieties of linings on the drawing are indicative of contrasting colors.

I claim:—

The ornamental design for a bag or analogous article, as shown and described.

PETER DAS.
